UNITED STATES PATENT OFFICE.

EUGENE JENOI AND STEVE KRUCHIO, OF THORPE, WEST VIRGINIA; SAID JENOI
ASSIGNOR OF ONE-HALF OF THE ENTIRE RIGHT TO STEVE KRUCHIO, ROZALIA
MARY SZABO, AND SARAH KRUCHIO, ALL OF UNIONTOWN, PENNSYLVANIA.

SPRING-HEEL.

1,094,211.

Specification of Letters Patent. Patented Apr. 21, 1914.

Application filed September 19, 1913. Serial No. 790,640.

To all whom it may concern:

Be it known that we, EUGENE JENOI and STEVE KRUCHIO, subjects of the King of Hungary, residing at Thorpe, in the county of McDowell and State of West Virginia, have invented certain new and useful Improvements in Spring-Heels, of which the following is a specification.

This invention relates to certain new and 10 useful improvements in spring heels.

The invention has for its primary object the provision of novel and effective means for obviating the usual jar incident to walking.

15 Briefly described, the invention comprises a detachable heel member that is secured to a yieldingly-mounted plate capable of movement within a shell or housing which latter is securely fastened to the shoe sole 20 at the heel of the shoe.

The invention consists in the novel construction, combination and arrangement of parts as will be hereinafter described and then claimed, and in describing the invention 25 in detail, reference will be had to the accompanying drawings forming a part of this specification and wherein like numerals of reference will be employed for indicating like parts throughout the different views, in 30 which:

Figure 1 is a perspective view of a shoe equipped with a spring heel in accordance with our invention, the shell or housing of the heel being partially in section to better 35 illustrate the parts. Fig. 2 is an enlarged vertical sectional view of a shoe heel in accordance with our invention, and, Fig. 3 is a horizontal sectional view taken on the line 3-3 of Fig. 2.

40 To put our invention into practice, we provide a shell or housing 5 open at its lower end, and having the general shape or outline of a boot or shoe heel, and which shell or housing is firmly secured in any desired manner to the shoe sole 6 at the heel 45 of such shoe. This shell or housing is preferably made of hard rubber, though of

course any desired material may be employed. Secured to the under face of the top or closed end of this shell or housing is 50 a plate 7, preferably made of metal, and suspended from said plate 7 by means of a plurality of springs 8 is a horseshoe shaped plate 9 closed at its forward end, also preferably of metal, and to which the heel proper 55 10 is detachably secured by fastening devices 11, here shown as in the form of screws, the heads of which lie within the countersinks 12 in the underneath face of the heel 10, the countersink being formed in the two 60 outer lifts of said heel. On the under face of the plate 7 are cushion blocks 14 so disposed as to be engaged by the sides and forward end of the plate 9, when the plate 9 recedes within the housing or shell 5 to that 65 extent where the springs 8 approach the limit of their compression, and at this time relieve the weight from said springs.

The main heel member 10 is preferably detachably-secured to the plate 9 so that the 70 same may be renewed when worn, without necessitating renewal of the remainder of the heel structure.

While in the drawings, we have shown a preferable embodiment of the invention as 75 practised by us, it will be evident that various slight changes may be made in the details of construction without departing from the general spirit of the invention as claimed.

Having thus described our invention, what 80 we claim as new and desire to secure by Letters Patent of the United States is:—

A spring heel comprising an inverted cup-shaped member secured to the heel portion of a shoe, a plate secured within said member, a transversely arranged cushioning block carried by said plate at the forward end thereof and extending completely across the plate, a second cushioning block arranged parallel with the first named block 90 and carried by said plate at a point spaced from the rear end thereof, a heel proper telescoping within the inverted cup-shaped member, a horseshoe shaped plate closed at

its forward end carried by the inner face of the heel proper, and cushioning springs extending between the two plates, the forward cushioning block adapted to engage the closed end of the horseshoe plate while the rearward cushioning block engages at its ends the sides of said horseshoe plates upon complete compression of said springs.

In testimony whereof we affix our signatures in presence of two witnesses.

EUGENE JENOI.
STEVE KRUCHIO.
